DESIGN FOR A NIPPLE OR THE LIKE

Christian W. Meinecke, East Orange, N. J.

Application June 2, 1933, Serial No. 48,257

Term of patent 14 years

To all whom it may concern:

Be it known that I, CHRISTIAN W. MEINECKE, a citizen of the United States, residing at East Orange, county of Essex, State of New Jersey, have invented a new, original, and ornamental Design for a Nipple or the like, of which the following is a specification, reference being had to the accompanying drawing, forming a part thereof.

Fig. 1 is a perspective view, in elevation, of a nipple, showing my new design, and

Fig. 2 is a bottom view of such nipple.

The dominant feature of the design resides in the ornamental appearance of the base as produced by the flange embodying a series of ogee curves.

I claim:

The ornamental design for a nipple or the like as shown and described.

CHRISTIAN W. MEINECKE.
